UNITED STATES PATENT OFFICE.

ONESIME HEBERT, OF OKLAHOMA, OKLAHOMA, ASSIGNOR TO UNIVERSAL CAR AND HOSE COUPLER COMPANY, OF PHOENIX, ARIZONA, A CORPORATION.

DRAWBAR AND COUPLING CONNECTION.

Original application filed September 1, 1916, Serial No. 118,103. Divided and this application filed December 3, 1917. Serial No. 205,102.

To all whom it may concern:

Be it known that I, ONESIME HEBERT, a citizen of the United States, and a resident of Oklahoma city, in the county of Oklahoma and State of Oklahoma, have invented certain new and useful Improvements in Drawbar and Coupling Connections, of which the following is a specification.

My invention relates to improvements in railway draft appliances, being more particularly an improvement in drawbar and coupler connections divided from my application for patent on car and train pipe couplers, filed September 1, 1916, Serial Number 118,103, and it consists in the constructions, combinations and arrangements herein described and claimed.

An object of my invention is to provide a drawbar and coupler connection for railway cars, which is at once flexible and arranged to adapt itself to all degrees of curvature in the track and differences of level between the cars.

Another object of the invention is to provide a drawbar and coupler connection including coacting means for gravitating the coupler head into normal alignment with the drawbar.

Another object of the invention is to provide a drawbar made in sections with a flexible connection therebetween, portions of the sections being so arranged to form a housing for the flexible connection.

Other objects and advantages will appear in the following specification, reference being had to the accompanying drawing, in which:

Figure 1 is a perspective view showing the drawbar and coupler connections turned with respect to each other.

Figure 2 is a vertical longitudinal section of the parts illustrated in Figure 1, portions being shown in side elevation.

Figure 3 is a horizontal section on the line 3—3 of Figure 2, and

Figure 4 is a cross section on the line 4—4 of Figure 2.

In carrying out my invention, I provide a coupler head 1 provided with the chamber illustrated in the drawing, in which the locking mechanisms of the coupler head described in my original application, are located. The chamber in the coupler head 1 has an opening 14 extending toward the rear.

A coupler pin 15 is carried by the coupler head 1 and extends through the opening or passage 14.

The end member 16 of a vertically flexible drawbar, has a horizontal pivotal mounting on the coupler pin 15. The head 16^a of the end member 16 is vertically offset with respect to the main body portion of the member 16. The shoulder 16^b which marks the offset between the end member 16 and the head 16^a, is located at a place to the rear of the plane of the rear surface of the coupler head. This arrangement at once provides the proper relative disposition of the drawbar with respect to the coupler head, and also provides ample space beneath the head 16^a for the relative vertical movement between the head 16^a and the coupler head.

A portion of the head 16^a to the rear of the coupler pin 15, is surmounted by a wedge shaped bridge 17 which includes the sides 75 sloping in opposite directions. The wedge bridge 17 cooperates with the oppositely inclined surfaces 18 formed in the top wall of the opening or passage 14.

The outer member 19 of the drawbar is 80 bifurcated at 20 to receive the end of a pivot pin 21 which passes through the end member 16. The end member 16 has a rearwardly extending plate 22 at the bottom. The outer member 19 has a forwardly extending plate 23 at the top. These plates are so formed and arranged that they provide a chamber or housing for a spring 24 bearing against the inner surfaces of the plates. The spring 24 is strong enough to keep the 90 two members of the drawbar in true horizontal alignment, and is also sufficiently strong to balance the weight of the coupler head 1 and the parts carried thereby. In the event of the vertical disalignment between the drawbar and the coupler head 1 or material differences in the relative heights between cars, the end member 16 of the drawbar will, of course, rotate accordingly on the pivot pin 21 and automatically adjust 95 itself to said differences in height, and in so doing, compress the spring. In the event of the restoration to the normal level of the cars or the uncoupling of the cars, the tension in the spring 24 will cause the restoration of the coupler head to the normal position in true alignment with the drawbar.

The operation of the device when taken in

connection with the foregoing description, will be readily understood. The drawbar and coupler head have relative horizontal swinging motion with respect to each other, 5 by reason of the connection of the head 16^a to the coupler pin 15. This connection is loose. The wedge bridge 17 and the inclined surfaces 18 have an inverted V shape. The weight of the coupler head 1 rests on the 10 wedge bridge 17. It therefore follows that, when any external influence causing the wedge bridge 17 to slide down one or the other of the inclined surfaces 18 as shown in Figure 1, is removed, the weight of the 15 coupler head 1 will again cause the apices of the wedge bridge and inclined surfaces to slide into coincidence and thus center the coupler head on the drawbar.

It will also be understood that should a 20 weight greater than that of the coupler head 1 act upon the coupler head illustrated in Figure 2, the coupler head would be depressed so that the end member 16 of the drawbar will swing in a vertical plane on 25 the pivot pin 21 and compress the spring 24 between the extending plates 22 and 23. The tension thus stored in the spring 24, will serve to return the coupler head 1 to the original and normal position when the 30 depressing influence is removed. The arrangement of the drawbar and coupler connection is a flexible one throughout. The coupler head 1 when turned to either side, will again gravitate into alignment with the drawbar.

35 When the coupler head is depressed out of alignment with the drawbar in a vertical direction, it will again return to the normal position through the action of the spring 24. The members of the drawbar have 40 movement with respect to each other, and the coupler head is capable of vertical and lateral movement with respect to the drawbar. The arrangement of the forward and rearwardly extending plates 23 and 22 of the 45 respective outer and end members of the drawbar, is simple and effective. The connection between the parts is tight enough to exclude the major portion of the foreign elements that fall upon the drawbar. The 50 chamber provided for the spring 24 is thus enclosed on all sides.

While the construction and arrangement of the device as illustrated in the drawing, is that of a generally preferred form, obviously, modifications and changes may be made without departing from the spirit of the invention or the scope of the claims.

I claim:

1. The combination of a draw bar, a coupling head having a rearward opening, said draw bar having a front end, offset above the general top surface of the bar, extending into said opening, said offset end being of less vertical and lateral dimensions than 65 the corresponding dimensions of the open-

ing, a vertical pivot uniting said offset end and coupling head so as to allow only a relative vertical sliding movement and a lateral swinging movement of said head, and cooperating cam surfaces on said head 70 and offset end adapted to bring the longitudinal axis of the head in line with the draw bar in response to the action of gravity on said head.

2. The combination of a draw bar having 75 its front end offset above the general surface of said bar, a coupling head having a rearward opening of greater vertical and lateral dimensions than the corresponding dimensions of said offset end, said offset end 80 entering said opening, a vertical pivot uniting said offset end and coupling head so as to allow only a relative vertical sliding movement and a lateral swinging movement of said head, and cooperating cam surfaces on said head and offset end disposed wholly in rear of the pivot, said cam surface tending to center the head with its longitudinal axis in line with the draw bar 85 in response to the action of gravity on said 90 head.

3. The combination of a coupling head having a rearward opening, a draw bar consisting of a main section and a short end section pivoted together on a horizontal 95 pivot, and having cooperating abutting surfaces preventing said end sections from being elevated materially out of alinement with the main section, a spring tending to hold said sections in alinement with said 100 abutting surfaces in contact, a vertical pivot for uniting said end section to said head within the rearward opening, the construction and proportions of said parts being such that the head may only slide vertically 105 and swing laterally, with respect to said end section.

4. The combination of a coupling head having a rearward opening, a draw bar consisting of a main section and a short end section pivoted together on a horizontal 110 pivot, and having cooperating abutting surfaces preventing said end section from being elevated materially out of alinement with said main section, a spring tending to hold said sections in alinement with said abutting surfaces in contact, the end section having an upward offset extremity extending within said opening, a vertical pivot uniting said offset end portion to said head, 115 and cooperating cam surfaces on said offset end and head tending to keep said head and draw bar in alinement, the construction and proportions of said parts being such that the head may only slide vertically 120 and swing laterally, with respect to said end section.

5. The combination of a coupler head having an opening therein extending toward the rear, a draw bar extending into 130

the opening in said head, the end of the draw bar within the opening being of less dimensions, measured vertically and laterally, than the opening in the coupler head, 5 a vertical pin uniting the end of the draw bar to the coupler head within said opening, in such manner as to permit relative vertical sliding and horizontal pivotal movement between said coupler head and draw bar, and cooperating plane cam surfaces on said head and draw bar tending to center said head with its longitudinal axis in line with the draw bar in response to the action of gravity on said head. 10

ONESIME HEBERT.
